UNITED STATES PATENT OFFICE.

SAÜL R. LIBERTY, OF PAWTUCKET, RHODE ISLAND

BOBBIN-HOLDER FOR SHUTTLES.

1,296,825.

Specification of Letters Patent. Patented Mar. 11, 1919.

Application filed July 29, 1918. Serial No. 247,224.

To all whom it may concern:

Be it known that I, SAÜL R. LIBERTY, a citizen of the United States, residing at Pawtucket, in the county of Providence and 5 State of Rhode Island, have invented certain new and useful Improvements in Bobbin-Holders for Shuttles; and I do declare the following to be a full, clear, and exact 10 description of the invention, such as will enable others skilled in the art to which it appertains to make and use the same.

My invention has for its object to provide extremely simple and inexpensive, yet highly efficient, reliable and durable means 15 for holding the bobbins of loom shuttles and the like in place upon the spindles and for releasing the bobbin automatically when the spindle is raised, the device being particularly well adapted for use upon looms employed in the weaving of duck and analogous fabrics, although it is not restricted to any particular type of shuttle.

With the foregoing object in view, the invention resides in the novel construction 25 hereinafter fully described and claimed.

In Figure 1 of the accompanying drawing, a longitudinal section of a portion of a shuttle is shown, equipped with the present invention, the bobbin or spindle being in 30 lowered or operative position.

Fig. 2 is a view similar to Fig. 1 showing the spindle and bobbin swung upwardly for removal of the latter.

Fig. 3 is a horizontal section on the plane 35 indicated by the line 3—3 of Fig. 1.

Fig. 4 is a vertical transverse section on the plane indicated by the line 4—4 of Fig. 1 showing the normal relation of parts.

Fig. 5 is a transverse section on the plane 40 indicated by the line 5—5 of Fig. 2 illustrating the manner in which the bobbin holding arms are spread when the spindle is raised.

In the drawing above briefly described, 45 the numeral 1 designates a common form of shuttle having the usual bobbin recess 2 and spindle 3, the latter being pivotally mounted at 4 for normal disposition in the recess 2 and for swinging upwardly therefrom as 50 seen in Fig. 2 when the bobbin 5 is to be removed or applied. Heretofore, numerous arrangements have been employed for automatically gripping the bobbin when the spindle is forced downwardly into the recess 55 and for releasing said bobbin when the spin-

dle is raised, but the majority of these devices have been comparatively complicated and expensive, yet have given little satisfaction, often damaging the bobbin. The present invention however aims to overcome 60 these difficulties by the provision of an extremely simple and inexpensive arrangement for accomplishing the same results as the devices mentioned. In attaining this end, I 65 provide the construction described below.

A pair of yielding arms 6, preferably in the form of flat springs—constructed of a single strip of metal, and disposed one on each side of the pivoted spindle end are provided, said arms being connected with said 70 end for movement bodily therewith. This connection may be effected in any one of a number of ways, but I preferably pass the pivot pin 4 of the spindle through the arms and in addition use one or more rivets 7 75 passing through the pivoted end of the spindle and through the arms in question. The free ends of the yielding arms 6 project into one end of the recess 2 and are provided with suitable bobbin holders 8 preferably formed by bending the ends of the arms inwardly as shown clearly in Fig. 3.

A pair of downwardly diverging release arms 9 have their upper ends pivoted at 10 upon a common axis to a metal plate 11 80 secured to one end wall of the recess 2, the lower ends of said arms being tapered and located between the spring arms 6 and the spindle 3, in the upward path of the latter (see Figs. 4 and 5). By this arrangement 85 when the spindle 3 is tilted upwardly to the position of Fig. 2, said spindle will engage the inner edges of the release arms 9 and force them apart as depicted clearly in Fig. 5, thus disengaging the bobbin holders 8 90 from the bobbin 5 and permitting the latter to be easily detached. When another bobbin is applied to the spindle and the latter forced downwardly into the recess 2, the arms 6 again move the holders 8 to operative 95 position.

A flat spring 12 is inset in a recess 13 in the bottom of the shuttle and bears eccentrically against the pivoted end of the spindle 3 to hold the latter in lowered position, 105 and the fixed ends of the arms 6 are preferably beveled at 14 for coaction with the beveled end 15 of the spindle in forming a flat surface for contact with the spring when said spindle is raised, whereby said spring 110

will also retain the spindle in the last named position.

From the foregoing taken in connection with the accompanying drawing, it will be obvious that I have provided an extremely simple and inexpensive bobbin holding means, yet one which will be highly efficient, reliable and durable. Since probably the best results are obtained from the details shown and described, they are by preference followed, but within the scope of the invention as claimed, considerable latitude is allowed for making such minor changes as occasion may dictate.

15. I claim:

In combination with a shuttle having the usual bobbin recess and a spindle pivoted

at one end to swing into said recess, a pair of yielding arms disposed one at each side of the pivoted end of said spindle and connected with the latter for movement bodily therewith, said arms having bobbin holders, and a pair of release arms pivoted at their upper ends in one end of said bobbin recess, and having downwardly diverging lower ends disposed between said spindle and said yielding arms and in the upward path of the former, whereby raising of said spindle will spread said yielding arms to release the bobbin.
